UNITED STATES PATENT OFFICE.

JOHN F. PETERS, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

STABILIZING AND POWER-FACTOR CORRECTING MEANS FOR ELECTRICAL CIRCUITS.

1,242,971.

Specification of Letters Patent. Patented Oct. 16, 1917.

Application filed March 4, 1916. Serial No. 82,079.

To all whom it may concern:

Be it known that I, JOHN F. PETERS, a citizen of the United States, and a resident of Edgewood Park, in the county of Allegheny and State of Pennsylvania, have invented a new and useful Improvement in Stabilizing and Power-Factor Correcting Means for Electrical Circuits, of which the following is a specification.

10 My invention relates to alternating-current distributing systems and especially to power systems adapted to deliver electrical energy to power-consuming devices in which the energy is employed in the form of electric arcs.

More particularly, my invention relates to distributing systems of the above-indicated character which are adapted to furnish power to electric arc-furnaces or other 20 power-consuming devices that depend for their operation upon the formation of electric arcs of substantially high-power capacity.

In furnaces of the electric-arc type which 25 are utilized for steel manufacturing purposes or for nitrogen fixation processes, the electric arcs employed are very unstable and tend to become disrupted when any slight disturbance affects their stability. The electrodes of such a furnace, on being consumed, must be properly regulated in order 30 to maintain the arcs which tend more and more to extinguish themselves as their lengths are increased. At the same time, the electrical system supplying power to an 35 electric-arc furnace operates at a relatively low power-factor. At best, however, the power-factor obtaining in the power system is totally inadequate to insure good operating 40 efficiency. This defect is more serious when several furnaces are supplied from the same power mains and required to be simultaneously operated therefrom.

Since the electric currents employed in 45 electric-arc furnaces are usually of extremely high values, the heating effects obtaining in portions of the circuit where such effects are extremely undesirable, may be very serious, at times, by reason of the extremely high valued wattless currents flowing 50 in the system. Because of the instability of the electric arcs employed in these furnaces and the low power-factor obtaining in the system, the control systems heretofore

employed in connection with such furnaces 55 to overcome the aforementioned defects have been, of necessity, very complicated and intricate requiring a great deal of attention on the part of operators.

My present invention is adapted to improve the power-factor of power systems supplying energy to electric-arc furnaces, and, at the same time, to stabilize the resultant arcs in order to insure their continuance during the operation of the furnaces. Both 60 of the aforementioned results may be jointly obtained when a plurality of electric-arc furnaces operating from a common supply circuit are available, since stabilizing means having different electrical qualities are associated with the arc-producing elements of 70 the separate furnaces to procure the aforementioned joint results, as will be herein-after described.

While the present description and drawing 75 are limited to electric-arc furnaces utilized for melting metal billets, it will be understood that my invention may be employed in any electrical power system furnishing power to power-consuming devices depending 80 upon the production of electric arcs for their operation. Among such devices may be mentioned those employed for the fixation of nitrogen, refining furnaces and a variety 85 of other uses.

To more fully understand my invention, reference may be had to the following description and the accompanying drawing, the single diagrammatic figure of which, for 90 illustrative purposes only, shows my invention employed in connection with a power system that furnishes current to electric-arc furnaces.

A three-phase alternator 1 is connected to a primary winding 2 of a step-down transformer 3, a secondary winding 4 of which is employed to transform the energy furnished by the alternator 1 into low-voltage and high-current energy. An electric-arc furnace 5 comprising three electrodes or arc-producing elements 6, and another similar furnace 7 having three similar electrodes 8 are connected to three mains 9 extending from the secondary winding 4 of the transformer. A charge 10, contained in the crucible of the furnace 5, is shown as metal billets which are to be melted by the electric energy supplied to the furnace. The melting

of the billets 10 is effected by the arcs that extend from the electrodes 6, each of which is connected to a main 9 of the three-phase supply circuit. In this particular instance, 5 the arcs are formed by reason of the current flow periodically extending between the three electrodes 6, as is characteristic of electric furnaces of this general type. The furnaces 5 and 7 being represented as identical, 10 the operation of one only will be explained, it being assumed that, with the exceptions to be mentioned, the operation of the other furnace is substantially similar.

The instability of the arcs extending from 15 the electrodes 6 has been previously explained, and it is well known that an electric arc may be made more stable by introducing some reactive element in circuit with it which will oppose rapid changes or variations 20 in the amount of electric current traversing, or the power introduced into, the arc. For instance, it will be apparent that a choke coil or inductive reactance device will perform the aforementioned function, namely, 25 that of opposing abrupt changes in the amount of electrical power obtaining in the circuit supplying current to the arc. To this end, I have introduced in each of the leads 11, connecting the electrodes 6 to the 30 power supply mains 9, a reactance coil 12 which, by reason of the inductive reactance afforded thereby, will stabilize the arc extending from each of the electrodes 6. In some types of furnaces, especially those of 35 large capacity, the inherent impedance or inductive reactance of the leads 11 may be sufficient to stabilize the arcs.

Of course, the reactance devices 12 will further decrease the power-factor obtaining 40 in the power circuit, and means should be provided for overcoming the inductive reactance imparted by the reactors 12 which will improve the power factor of the circuit and insure economical and efficient operation 45 of the system. To this end, I introduce in each lead 13 which extends to the electrodes 8 of the furnace 7, condensive reactance elements 14. The condensers 14 are preferably not connected directly in circuit, 50 but are associated with series transformers 15 having their primary and secondary turns so proportioned that the condensive reactance afforded by the condensers 14 may be made adequate while condensers of small 55 capacity only are utilized. The condensers 14, which are usually adapted for high-voltage operation, perform a double function, one of which is to stabilize the arcs extending from the electrodes 8, and the other of which is to 60 neutralize the inductive effects introduced in the power system by reason of the insertion of the inductive reactance elements 12. As a result, the inherent low power factor resulting from the arc furnaces alone is 65 proved. The capacity of the condensers 14

need not necessarily be so high as to establish unity power factor in the system when the furnaces 5 and 7 are simultaneously operated, but their capacity should be such as to insure an economical operation of the 70 power system whereby the power-factor obtaining therein may compare favorably with other power systems furnishing power to consuming devices.

From the foregoing description, it will be 75 noted that I have provided means for stabilizing the arcs produced in electric arc-furnaces and, at the same time, have selected the stabilizing devices so that by their separate actions upon the system, the resultant 80 power-factor of the system may be increased to a sufficiently high value to insure economical operation of the system.

While my description has been limited to one application only, namely, that of electric arc furnaces, it will be understood that 85 my invention may be employed in connection with a variety of electric arc utilizing devices which impart, by reason of their inherent qualities, undesirable electrical characteristics to the system that should be improved to insure economical operation thereof, and I desire, therefore, that only such limitations shall be imposed upon my invention as are indicated in the appended 90 claims.

I claim as my invention:

1. The combination with an alternating-current power-supply system and a plurality of electric arc utilizing devices connected thereto, of means severally possessing diverse electrical characteristics and severally associated with said devices for both stabilizing the attendant electric arcs produced and improving the power-factor obtaining in the supply system. 100

2. The combination with an alternating-current power-supply system and a plurality of electric arc-utilizing devices connected thereto, of stabilizers severally possessing diverse electrical characteristics and associated with the arc-producing elements, said stabilizers being so selected that, in combination, the value of the power-factor obtaining in the supply system may be controlled. 110

3. The combination with an alternating-current power-supply system and a plurality of electric arc-utilizing devices connected thereto, of inductive reactors only inserted in circuit with some of the electric arcing elements, and condensive reactors only inserted in circuit with others of the electric arcing elements, said condensive and inductive reactors stabilizing their attendant 120 electric arcs and, in combination, regulating the power-factor of the supply system.

4. The combination with an alternating-current power-supply system and a plurality of electric arc furnaces having their 125

electrodes connected thereto, of stabilizers possessing inductive characteristics only connected in series circuit with some of the electrodes, and stabilizers possessing condensive characteristics only connected in series circuit with others of the electrodes in order to stabilize the attendant electric arcs, said stabilizers, in combination, being so selected that the power-factor obtaining in the power-supply system may be improved over that normally obtaining therein.

5. An alternating-current distributing system comprising power-supply mains, a plurality of electric arc-utilizing devices connected thereto which inherently establish a low power factor in the system, and means severally possessing diverse electrical characteristics and severally associated with the electric arcing elements which both stabilize 10 the attendant electric arcs and increase the

value of the power-factor normally obtaining in the system.

6. An alternating-current distributing system comprising power-supply mains, a plurality of electric arc-utilizing devices connected thereto which, of themselves, inherently establish a low power factor in the system, and stabilizers possessing inductive reactance only associated with some of the electric arcing elements, and stabilizers possessing condensive reactance only associated with others of the electric arcing elements, said reactors stabilizing the attendant electric arcs and, in combination, providing means for increasing the value of the power 25 30 35 factor normally obtaining in the system.

In testimony whereof, I have hereunto subscribed my name this 29th day of Feb., 1916.

JOHN F. PETERS.
